AMMUNITION PACKING DEVICE

Parley F. Lambert, Arlington, Va.

Application November 1, 1945, Serial No. 626,159

5 Claims. (Cl. 226—19)

(Granted under the act of March 3, 1883, as
amended April 30, 1928; 370 O. G. 757)

1

The invention described herein may be manufactured and used by or for the Government for governmental purposes, without the payment to me of any royalty thereon.

This invention relates to methods of and devices for packing belted machine gun ammunition.

An object of this invention is to provide a method of folding and arranging belted machine gun ammunition to facilitate packing same in ammunition boxes.

Another object of the invention is to provide a new and improved layout of the folds of the belt containing the ammunition in order to reduce the number of sharp folds of the belt and to minimize the sharpness of the fold and the resultant stress on the belt at the folds.

A further object of the invention is to provide a means whereby the stress on the individual rounds of ammunition is minimized thus preventing damage to any of the rounds.

Other and further objects and advantages of the invention will become apparent from the following description of a preferred embodiment thereof, as illustrated in the accompanying drawings and in which,

Figure 1 is a front elevation of the ammunition packing device showing belted ammunition on the rack and empty ammunition box beneath,

Figure 2 is a sectional elevation taken along line 2—2 of Figure 1,

Figure 3 is a sectional view taken along line 3—3 of Figure 2,

Figure 4 is a sectional view taken along line 4—4 of Figure 2,

Figure 5 is a sectional view taken along line 5—5 of Figure 2,

Figure 6 is a top view of the device, partly broken out to show the mechanism,

Figure 7 is a detail plan view of the lever guide plate with upper belt tip pin,

Figure 8 is a detail side elevation of the plate and pin shown in Figure 7,

Figure 9 is a detail elevational sectional view showing the method of mounting one of the upper belt guide pins,

Figure 10 is a detail elevational sectional view showing the swivel joint method of supporting the actuating lever, and

Figure 11 is a perspective partly phantom view of the device to show the general arrangement of the parts and mechanism.

As best shown in Figures 1, 2 and 11, the ammunition loading fixture has a base member 2 made of sheet material on which is supported an upright box-like frame or casing 4 which has a front face member 6, two side members 8 and 10, and a top member 12. The side members may be turned in at the bottom as at 14 and 16 respectively to furnish abutting surfaces resting on the

2

base member 2 so that the portions 14 and 16 may be welded to the base member 2.

The base member 2 is greater in area than the horizontal cross sectional area of the frame 4 which rests upon it, so that the frame may be located toward the rear of the base member 2, thus providing a front platform 18 upon which an empty ammunition box or container 20 may rest during part of the loading operation. Greater stability is also the result of thus providing a base member 2 the area of which is greater than that of the frame 4 resting thereon.

A pin retaining plate 22, substantially rectangular in area, is secured to the inner surface of the front face member 6 as shown, by welding or other suitable fastening means, the plate 22 being made longer than the width of the face member 6 so that the two end portions 24 and 26 of the plate 22 extend to the right and left respectively beyond the side edges of face member 6 as shown.

As seen in Figure 4, suitable vertical slots or apertures 28 and 30 are formed in side members 8 and 10 to permit the insertion of the ends 24 and 26 of the plate 22 therethrough. Left and right end pin retaining plates 32 and 34 are fastened to the front surfaces of ends 24 and 26 of plate 22 with their front faces flush with the face of face member 6, as illustrated. A horizontal pin support plate 36 formed of an elongated piece of angle iron, has its vertical leg 38 fastened to the rearward face of plate 22 as may be seen in Figures 4 and 9, with its horizontal leg 40 projecting horizontally and rearwardly. End pin support plates 42 and 44, as seen in Figure 4 similar in vertical cross section to support plate 36, but shorter, are fastened to the rearward faces of end portions 24 and 26 respectively, thus constituting sidewise extensions of pin support plate 36.

A plurality of L-shaped ammunition belt guide pins 46 formed of round rods, are disposed as shown with their horizontal legs 47 extending through holes 48 in members 6 and 22 and projecting forwardly out of the mechanism as shown, and with their vertical legs 50 extending downward through holes 52 in horizontal leg 40 of support plate 36. The side end pins 49 and 56 extend through similar holes formed through the sidewise extensions such as members 34, 24 and 44 already described. For use with a standard 250 round, caliber .30 ammunition belt, a total of eight belt guide pins 46 will suffice. The number of pins 46 required will of course vary depending upon the length of belt being used. The members 36, 42 and 44 may be fastened to plate 22 by means of screws 54 to permit easy assembly of the surrounding cooperating parts and positioning of the pins 46, 49 and 56.

As illustrated in Figures 1 and 2, a belt guide pin holder 57 comprising a hollow cylindrical

member is welded at its forward end to the rearward face of face member 6 in registry with a hole 58 formed through member 6 as shown. A lower belt guide pin 60 is slidably inserted through the central horizontal bore in holder 57 and the hole 58 and adapted for reciprocal movement therein. The pin 60 is formed of cylindrical rod material and, as shown in Figures 2, 5 and 11, has its rearward end bent into a ring at 62, the axis of the ring being substantially vertical.

A hand lever 64 has its lower end 66 pivotally supported in a lever retaining plate 68 which is welded to the bottom base member 2. As best illustrated in Figure 10 the lower end 66 of the lever 64 is suitably formed with a circumferential groove near the end so as to permit the groove to rest in a central hole 70 formed in the central elevated portion 72 of the plate 68. The plate 68 is split along a plane passing vertically through its center, thus forming two halves which are brought together after the lower end 66 of the lever 64 is placed between them, whereby the grooved portion of the lever is loosely disposed in the hole 70.

As shown in Figures 2 and 11, lever 64 extends upward through the ring 62 of guide pin 60. The upper portion of lever 64 extends upwardly through a slot 74 in top member 12 of the mechanism. Thus the protruding portion of the upper end of lever 64 may be grasped with the hand of the operator and moved back and forth, its motion being constrained by the dimensions of the slot 74, so that as the lever 64 is thus pivoted on base plate 68 between positions 65 and 67 in Figure 2, the pin 60 is alternately caused to protrude forwardly out of the hole 58 to the position 76 as shown by the dotted lines in Figure 2, and to be retracted inside hole 58 to the position indicated by the solid lines at 78 in the same figure.

As seen in Figures 2, 3 and 4 and in detail in Figures 7 and 8, a lever guide plate 80 is formed of an elongated piece of sheet metal with a longitudinal elongated slot 82. Its rearward end portion 84 is reduced in width, thus forming shoulders at 86. Its forward end is bent over at 88 and a belt tip pin 90 has its threaded rearward end inserted through a hole in the bent portion 88, being secured therein by two nuts 92. As best seen in Figure 2, the plate 80 is horizontally disposed just beneath the top member 12 of the device, with its slot 82 in longitudinal registry with slot 74 of member 12. The rearward extension 80 extends through a horizontal slot 81 formed in the downward hanging portion 13 of the top member 12. The pin 90 extends forwardly through aligned holes 91 and 92 in face member 6 and in both legs of U-shaped pin support member 96. The slot 82 is shorter than slot 74 and lever 64 extends through both slots.

It is thus apparent that movement of lever 64 from position 65 as shown in Figure 2 to position 67, will not only move pin 60 from its rearward position to its forward protruding position 76 but will also move lever guide plate 80 from its rearward position as shown by the solid lines in Figure 2 with shoulders 86 up against the inside of slot 81 and portion 84 protruding out rearwardly, and pin 90 not extending forwardly out of hole 92, to the forward position as shown by the dotted lines in Figure 2. In this position the pin 90 protrudes forwardly out

of hole 92 and the portion 84 correspondingly does not protrude rearwardly out of slot 81.

As will be explained below, it is desirable for the reciprocal range of movement of upper pin 90 responsive to lever 64 to be less than that of lower pin 60 even though the effective lever arm of lever 64 about pivot 68 is greater at upper pin 90 than at lower pin 60, and this is accomplished by the structure shown. Referring now to Figure 2, it will be seen that as the hand lever 64 is moved to its forwardmost position 67 i. e. to the left of the view, the pins 60 and 90 protrude fully from the face 6 of the device as shown by the dotted outlines. Then, as lever 64 is moved toward its rearward position 65, i. e. toward the right of the view, the ring 62 of lower pin 60 encircling the lever 64 must necessarily be carried along a distance equal to the movement of the lever 64 at that location. But the upper portion of lever 64 which extends through the slot 82 in member 80 does not, as it moves to the right, cause the member 80 to move to the right until the lever has reached the location 94 at which point the lever has traveled the full length of slot 82 and has now come into contact with the right hand end wall 83 of the slot. Then, as lever 64 continues its rightward movement from position 94 it carries along with it the member 80, causing the forward end of pin 90 to be retracted inside hole 92 and the rearward end 84 of member 80 to protrude out of slot 81. Then the rightward movement of lever 64 is arrested at location 65 when it reaches the right end wall 75 of slot 74 in top member 12. Lower pin 60 is also retracted inside hole 58 of front member 6 at this time as already explained.

The device may be employed for packing belted machine gun ammunition into the ammunition boxes commonly used on or with machine guns, the belted cartridges being drawn from the box into the gun. An empty ammunition box 20, with its lid 21 pivoted to open position as shown, is placed on the front platform 18 as shown in Figures 1 and 2, below the pins 46, 49 and 56, and the hand lever 64 is moved to its forward position 67 as seen in Figure 2, so that pins 60 and 90 protrude fully from the front face member 6. An L-shaped spring catch 63 secured at one leg to member 36 as shown, serves to yieldingly engage lever 64 and hold it in its forward position 67 as desired.

A belt 97 loaded with cartridges 98 has its metal end piece 100 placed in the position shown in Figures 1 and 2, with its end loop 102 surrounding and supported on pin 90. The end piece 100 is the part of the belt which is the first to pass through the machine gun during loading and firing. The belt is then looped down around lower pin 60 and up and over pin 104, and then down and around pin 60 again and up and over pin 106, then down again and around lower pin 60, and up and over the next of the pins 46, and so on, to one side and the other as illustrated until the entire belt is in position on the pins as shown, in a series of U-shaped folds or layers 107 one layer inside the other, the end 108 of the belt containing no cartridge and being hung onto end pin 49. Although the illustration shows some space between the cartridges of adjacent coils or layers, this is only for clarity of illustration. In practice there will be no such space, each layer being necessarily in contact with the adjacent layers.

Now the hand lever 64 is pushed to its rearward position 65, thus retracting the pins 60 and

90 whereupon the end piece 100 of the belt will drop down to left or right and lie across the top of the loops carried on the pins 46.

The empty ammunition container 20 is then moved upwardly by the operator so the down-hanging layers 107 go into the box 20, and, as the top edge 23 of the box 20 gets close to the pins 46 the box 20 is pulled toward the operator and away from face member 6 so that the pins no longer support the belt, and it drops into the box 20. The cover 21 is then closed and the filled box is ready for immediate use if desired.

Where the belt is no longer than standard, then the end of the belt, instead of being hung on pin 49 as explained, is looped over pin 49 as shown by the dotted line 55. Similarly, if the belt is too short to reach pin 49 the end of the belt 97 may be looped over right hand pin 56 as shown by the dotted line 57 the loose end being tucked between the end and next to end layers.

By means of the above described invention it is possible to pack belted ammunition into ammunition boxes at a speed greatly in excess of that previously attained, and with relatively untrained and unskilled labor. The ammunition is packed into the box more uniformly and fills the space with less crowding. In the old method it was customary to lay the belt into the box in a plurality of superposed horizontal layers with bends at the ends of the layers. There were usually about 13 or 14 folds or end bends made in packing each belt of calibre .30 ammunition, with resultant waste of the space around each fold. The bends were on top of each other at each end and had to be relatively sharp to allow the belt to fill the box. In many cases, due to inexperienced personnel, the belt did not go all the way into the box, and downward pressure necessary to permit closing the box caused the bends at the ends of the horizontal layers to be subjected to such great stress that the end cartridges were sometimes deformed and caused the gun to jam when used. By the present method of packing as disclosed herein, there are only 7 or 8 folds per belt. Thus the number of folds or end bends has been cut in half with substantially less space wastage.

In the present method, all the end bends are on top and hence are not subjected to pressure. The layers 107 are of relatively large radius and thus are flexible and easily accommodate themselves to the interior contour of the box so as to completely fill it along the bottom and sides. Thus the belt need not be pressed down into the box to close the cover, since it does not protrude upwards, and possible damage to individual rounds is avoided.

Although a preferred embodiment of the invention has been described in specific terms, it is to be understood that changes may be made in size, shape, materials and arrangement without departing from the spirit and scope of the invention as claimed herein.

I claim:

1. A method of arranging belted machine gun ammunition for packing into a machine gun ammunition box, comprising folding the belt into a nest of substantially U-shaped graduated layers each layer lying within the one next larger and being joined to it at one end and being joined to the layer next smaller at the other end, with the joined ends of said nested layers uppermost.

5 2. A method of arranging belted machine gun ammunition for packing into a machine gun ammunition box, comprising folding the belt into a nest of substantially U-shaped graduated layers each layer lying within the one next larger and being joined to it at one end and being joined to the layer next smaller at the other end with the joined ends of said nested layers uppermost, the end of said belt which is to enter the machine gun first forming the innermost and smallest layer and having the metal tip portion of the belt protruding therefrom.

10 3. A method of packing a belt of machine gun ammunition into a machine gun ammunition box, comprising arranging said belt inside said box in a nest of substantially U-shaped graduated layers, each layer lying within the one next larger and being joined to it at one end and being joined to the layer next smaller at the other end, the joined ends of said nested layers being uppermost in said box and the end portion of said belt which is to enter the machine gun first forming the innermost and smallest layer.

15 4. A rack for arranging a belt of machine gun ammunition into a nest of substantially U-shaped graduated layers for packing into a machine gun ammunition box with the joined ends of adjacent layers uppermost comprising a flat supporting member, a plurality of spaced parallel belt guide pins mounted on said member in a line laterally thereof with each pin projecting therefrom, a lower belt guide pin slidably mounted through said member below the center of said line of guide pins and extending parallel to said pins and upper belt tip pin slidably mounted through said member above the center of said line of guide pins and extending parallel to said pins and means for sliding said upper belt tip pin and said lower belt guide pin through said member into and out of engagement with said belt as desired.

20 5. A rack for arranging a belt of machine gun ammunition into a nest of substantially U-shaped graduated layers for packing into a machine gun ammunition box with the joined ends of adjacent layers uppermost comprising a flat supporting member, a plurality of spaced parallel belt guide pins mounted on said member in a line laterally thereof with each pin projecting therefrom, a lower belt guide pin slidably mounted through said member below the center of said line of guide pins and extending parallel to said pins, an upper belt tip pin slidably mounted through said member above the center of said line of guide pins and extending parallel to said pins, a pin retracting lever pivoted at its lower end on said support and with its upper end adapted for movement by an operator and said lever engaging said tip pin and guide pin intermediate its ends for retracting or 25 extending said pins through said member as desired.
